UNITED STATES PATENT OFFICE.

JOSEPH J. S. LIST, OF ROCKDALE, NEAR SYDNEY, NEW SOUTH WALES.

PIPE-CO尤LING.

SPECIFICATION forming part of Letters Patent No. 465,868, dated December 29, 1891.

Application filed August 28, 1890. Serial No. 363,382. (No model.)

To all whom it may concern:

Be it known that I, JOSEPH JAMES SWITHIN LIST, joiner, a subject of the Queen of Great Britain, residing at Rockdale, near Sydney, 5 in the British Colony of New South Wales, have invented a new and useful Pipe-Coupling, to be used as an improved railway-brake pipe-coupling, applicable also for other coupling purposes, of which the following is a 10 specification.

This invention relates to a pipe-coupling specially useful for coupling up the brake-pipes of adjoining vehicles of a railway-train, although it may be used for coupling up any 15 pipes, and particularly those carrying fluids under pressure. It has been specially devised in order to provide a reliable and easily-manipulated coupling, cheap in construction and durable in operation. An improved rail- 20 way-brake pipe-coupling, applicable also for other coupling purposes, according to this invention is constructed in two halves, which will gear one into the other when each has its outlet closed, and having been so geared 25 are capable of each being revolved an eighth-turn in order to open the exits to form a through-passage between the pipes. Each of these half-couplings is made with a hollow frusto-conical plug-tap set at right angles to 30 the line of pipes, the outer and smaller end of which plug is provided with a handle and the inner or larger end of which terminates in two quadrants diametrically opposite one another and protruding slightly beyond the 35 face of the coupling. In the barrel of the plugs or taps are stops, so that the plugs may only be revolved an eighth of a turn. In the face of the coupling, which is at right angles to the axis of the plugs or taps, is a seating 40 of india-rubber. At the back of the face are quadrant-keeps and on the edge of the coupling are quadrant-wards adapted to take under the keeps, such wards being also provided with stop-pins. The center line of the 45 half-coupling end pipe on which the through-pipe takes is in a plane parallel with the face of the coupling, and its port or passage is connected with the barrel of the tap, so that when the plugs are set at one end of their 50 eighth-revolution there is no exit through the half-coupling from said pipe, but when at the other end of its revolution the plug or tap

and the port or passage are open to the atmosphere. The plugs, the stops, and the quadrants are so arranged that when the half-couplings are free their exits may be opened and closed by the outside handles, and when the exits are "open" the half-couplings can-not be geared. 55

In order that this invention may be clearly 60 understood, reference will now be made to the drawings herewith, in which—

Figure 1 is a section of a brake-pipe coupling constructed according to this invention, and Fig. 2 a face view of a "half" of the 65 same constructed according to these improvements.

A a are barrels or casings.

B b is a conical plug.

C c are through-pipes and junctions.

A' a' are coupling-faces.

A² a² are quadrant-keeps, and A³ a³ quadrant-wards.

A⁴ a⁴ are stop-pins.

A⁵ a⁵ are rubber seatings.

A⁶ a⁶ are packing-nuts.

A⁷ a⁷ is a fixed washer.

A⁸ a⁸ are lugs or stops.

B' b' are quadrant ends, and B² b² recesses formed thereby.

B³ b³ are hollows of plugs.

B⁴ b⁴ are openings or ports.

B⁵ b⁵ are handles.

B⁶ b⁶ are washers.

B⁷ b⁷ are nuts.

B⁸ b⁸ are square ends.

B⁹ b⁹ is a screw.

C' c' are ports or passages to plug-taps.

To "couple up" pipes on which these half-couplings are fixed, said halves are placed 90 face to face with the seatings A⁶ a⁵ meeting and the barrels or casings A a in juxtaposition, when the quadrants B' will gear in the recesses b² and the quadrants b' in the recesses B². A quarter-turn is then given to 95 the half-couplings, each of them taking half of it or an eighth-turn. By this means the quadrant-wards A⁸ and a³ are brought under their respective keeps A² and a², and the "turn" is stopped by pins A⁴ a⁴. The said 100 wards and keeps press the seatings tightly together and lock the coupling. The quarter turn given to the half-couplings A and a causes the geared quadrants B' b' to turn their re-

spective plugs B and b until the quadrants are arrested by the stops A⁸ a⁸, when the ports B⁴ b⁴ are opposite to the respective passages C' c' and through communication is opened 5 from one pipe to the other.

To uncouple the brake-pipe the operation is reversed, the casings being moved so that the wards are moved out from under the keeps and at the same time moving the plugs

- 10 B and b by the quadrants B' b', so that the ports B⁴ b⁴ are closed against the passage of air when the seatings A⁵ a⁵ are drawn asunder. The port B⁴ may be opened with the passage C' when uncoupled by turning handle B⁵,
- 15 which fits on the end of the plug; but it is not possible to couple up if both or one of the half-couplings has its port B⁴ open to passage and thus open to air, for if the quadrants B' be in other than the position due to the closed 20 plug or cock B they cannot gear with the quadrant-recesses of another half-coupling.

Having now particularly described and explained the nature of this said invention and the manner in which the same is to be performed, I declare that what I claim is—

In a pipe-coupling, the combination of the two halves, each provided with a tapering valve-plug, said plugs having their larger ends turned toward each other, the washers A⁷ a⁷, fitting the inner ends of said plugs, and the rubber seatings A⁵ a⁵, supported by said washers, the nuts A⁶ a⁶, confining said seatings and separated, and the exterior handles and interior quadrants connected with said plugs, substantially as set forth. 25
